SPECIFICATION forming part of Design No. 15,159, dated July 22, 1884.

Application filed June 9, 1884. Term of patent 14 years.

To all whom it may concern:

Be it known that I, THOMAS C. HUDSON, of the city and county of Providence, and State of Rhode Island, have invented and produced a new and original Design for a Badge; and I do hereby declare the following specification, taken in connection with the accompanying drawing, forming a part of the same, to be a description thereof.

10 As shown in the drawing, the design consists of a banner or flag, A, a cross, B, and a branch of laurel or other leafy branch, C. With these parts may be combined a ribbon-scroll, D, and upon the scroll may be placed 15 any preferred letters, word, or words; but such letters, word, or words form no part of the design.

The banner or flag A may bear a monogram, as shown, or any preferred letters, word, or

words, such monogram, letters, word, or 20 words forming no part of the design, however, the essential features of which are a banner or flag, a cross, and a leafy branch with or without a ribbon-scroll.

What I claim, and desire to secure by Letters Patent, is—

1. The design for a badge herein described, consisting of a banner or flag, a cross, and a leafy branch, substantially as set forth.
2. The design for a badge herein described, 30 consisting of a banner or flag, a cross, a leafy branch, and a ribbon-scroll, substantially as set forth.
